UNITED STATES PATENT OFFICE

AUGUST EGERER, OF GREAT NECK, NEW YORK

DESIGN FOR A SWEATER OR ARTICLE OF SIMILAR NATURE

Application filed May 13, 1930. Serial No. 35,634. Term of patent 3½ years.

To all whom it may concern:

Be it known that AUGUST EGERER, citizen of the United States, and resident of Great Neck, in the county of Nassau and State of New York, has invented a new, original, and ornamental Design for Sweater or Article of Similar Nature, of which the following is a specification, reference being had to the accompanying drawing, forming part thereof, in which the figure is a perspective view of a sweater embodying my new design.

I claim:

The ornamental design for a sweater or article of similar nature, substantially as shown.

Dated, April 17th, 1930.

AUGUST EGERER.
